AIR BLAST GIN WITH VALVE CONTROLLED
PNEUMATIC MOTE DISCHARGEJeffrey J. Wallace, Amite, La., assignor to Gullett
Gin Company, Amite, La., a corporation of
Louisiana

Application October 6, 1941, Serial No. 413,860

6 Claims. (Cl. 19—58)

This invention relates to air blast gins of the pneumatic moting type, in which air under pressure from a common reservoir supplies two nozzles, the lint removing nozzle and a nozzle in the moting chamber directing a blast into the mote discharge flue for evacuating the motes and trash thrown off centrifugally into the moting chamber by the saw cylinder.

The moting nozzle may be so positioned that it has a venturi action with respect to the atmosphere within the moting chamber, causing a drift of the suspended matter in said chamber toward the mote discharge duct, and counter-acting the down draft caused by the rotation of the saw cylinder with its rim of cotton through the moting chamber toward the lint flue, which down draft would carry the suspended matter into the lint flue.

Ordinarily, there is no means for varying the volume of air supplied to the moting nozzle independently of the air supplied to the lint nozzle.

It is, however, highly advantageous to have such a variable volume control for the moting nozzle, inasmuch as cotton from different fields may vary greatly as to the condition and lightness of the staple and the amount of motes and trash, so that if the lint is unusually light or non-adhesive to the saws there is danger that it may be drawn off by the induced air drift in the moting chamber under strong blast conditions and discharged with the motes. Under these circumstances a diminished moting blast is desirable.

Conversely, if the cotton is unusually trashy, an increased moting blast is advantageous to clear the mote chamber of the centrifugally thrown trash and motes as fast as it is produced, to minimize collections of the trash particles in the moting chamber which create turbulence and tend to break up the orderly progress of the drift toward the mote discharge duct.

The object of the present invention, therefore, is to provide, in a gin of the type described, a volume varying valve in the conduit from the common compressed air reservoir to the moting blast nozzle.

Another object of the invention is to provide a capacious auxiliary reservoir between the valve and the moting blast nozzle, serving the latter, to prevent the throttling of the valve having localized velocity effects in any portion of the linear extent of the blast issuing from the moting nozzle.

Other objects of the invention will appear as the following description of a preferred and practical embodiment of my invention proceeds.

In the drawing which accompanies and forms a part of the following specification, and throughout the figures of which the same characters of reference have been used to denote the same part:

Figure 1 is a side elevation of a cotton gin embodying the principles of the invention; and

Figure 2 is a cross-section taken along the line 2—2 of Figure 1.

Referring now in detail to the several figures, the gin therein illustrated is of the type disclosed in and covered by my Patent No. 2,253,456, granted August 19, 1941, in which there is a saw cylinder 1, the saws of which operate between the ginning ribs 2, and in which a pneumatic mote discharge duct 3 has a flared mouth 4, forming a moting chamber confronting the saw cylinder in the region adjacent its emergence from the ribs 2 at which region the motes and trash are centrifugally thrown from the saw cylinder. This particular gin is characterized by the fact that the floor 5 of the moting chamber is planiform and that a moting blast nozzle 6 directs an air blast in sheet-like form along the floor 5 and into the mote discharge duct 3. The inclination of the floor 5 with respect to the trajectories of the centrifugally thrown motes is such that the motes and trash are thrown directly into the sheet-like blast from the nozzle 6 and whisked away into the mote discharge duct. The sheet-like blast, entering the relatively narrow mote discharge duct 3, has a venturi action in creating a drift of the atmosphere in the moting chamber 4 in a direction away from the saw cylinder toward the mote discharge duct, carrying the lighter suspended matter into said duct and at the same time producing a mild suction at the point 7, where the saw cylinder passes the moting blast nozzle 6 counteracting the down draft created by the saw cylinder, which of course, is moving in the direction indicated by the arrow. Thus, normally the suspended matter in the atmosphere of the moting chamber 4 is prevented from being carried downwardly by the said down draft. Below the moting chamber is the nozzle 8 which directs a lint removing blast tangentially of the saw cylinder towards the points of the saw teeth and carries the lint into the lint flue 9, which is evacuated by a suction fan, not shown, but which is conventional in the art. The air under pressure which supplies both the lint removing blast at the nozzle 8 and the moting blast at the nozzle 6 is derived from a reservoir or conduit 10 supplied by a blower, not shown. Said reservoir communicates with the

moting blast nozzle 6, by means of a conduit 11, making a T connection with a pipe or auxiliary reservoir 12, having an open side communicating with the moting blast nozzle 6.

In the gin, as disclosed in my aforementioned patent, the compressed air from the reservoir 10 is supplied with equal pressure, both to the moting blast nozzle 6 and the lint removing blast nozzle 8.

It has been pointed out in connection with the objects of the subject invention that there are times when it is desirable to control or vary the volume of air supplied to the moting blast nozzle. For example, when the staple is light or short and only feebly adherent to the saw teeth, there is a tendency for much lint to be drawn off into the moting chamber if the drift of the atmosphere of said chamber toward the mote discharge duct is strong, due to a powerful moting blast. Under such conditions it is desirable to decrease the volume of air supplied to the moting blast nozzle. Conversely, when the cotton is particularly dirty, so that there is an unusually large quantity of motes and trash particles centrifugally discharged into the moting chamber it is desired to get rid of these as fast as possible, otherwise, a condition of turbulence is set up in the atmosphere of the moting chamber, due to congestion of motes and trash therein with the innumerable collections between particles attendant upon such congestion and which tends to nullify the venturi action of the moting blast so that suspended trash and motes will be carried down to the lint removing blast in the down draft produced by the rotation of the saw cylinder. Under such conditions the moting blast should be increased.

The present invention provides the desired variable control of the moting blast by the interposition of a valve 13 to control the volume of air passing from the reservoir 10 through the conduit 11. Figure 2 shows that the pipe or auxiliary reservoir 12 is extended beyond one side of the moting blast nozzle 6, as indicated at 14, and that the conduit 11 communicates with the reservoir 12 through this extension. The extension 14 is open at its end and receives the valve 13 which is in the form of a sleeve 16 rotatably fitting within said extension and having a closed end 17 with an extended flange 18 affording a hand hold for operating said valve. The sleeve 13 has a semicylindrical portion 19 adapted to fully or partially occlude the conduit 11 or to leave said conduit fully open when the valve is in the position shown in Figure 2.

It will be well understood by those skilled in the art that when the valve is partially closed, the velocity of the air column passing through said valve will be increased, so that if the conduit 11 and the valve 13 were placed anywhere in the zone of the moting blast nozzle 6 there would be a localized increase in the velocity of the moting blast in the region adjacent said valve. This would be undesirable, in that for optimum efficiency the velocity of the moting blast should be uniform throughout the linear extent of the moting blast nozzle. The positioning of the conduit 11 and the valve 13 in the endwise extension 14 of the auxiliary reservoir 12, and entirely out of the zone of the moting blast nozzle, prevents any localized velocity effects on the blast issuing from said nozzle, and the uniformity of the velocity of the moting blast throughout its linear extent is further assured by the relative capaciousness of the auxiliary reservoir 12 which is of sufficient

size to equalize the pressure of the air before it issues from the moting blast nozzle.

It will, of course, be understood that in the operation of this valve, when it is desired to vary the intensity of the moting blast, the valve is turned so as to more or less partially occlude the cross-sectional opening of the conduit 11. The shape of the valve 13, being that of a hollow cylinder open at its inner end, it interposes no structural impediment to the passage of the full volume of air from the reservoir 10 to the moting blast nozzle when the valve is in its fully open position, as illustrated in Figure 2.

The valve may be readily removed, should occasion require, by drawing it longitudinally from the end of the extension 14, in which extension it makes a friction fit.

While I have in the above description disclosed what I believe to be a preferred and practical form of the invention, it will be understood to those skilled in the art that the specific details of construction and arrangement of parts as shown, are by way of example and not to be construed as limiting the scope of the invention defined by the appended claims.

What I claim as my invention is:

1. Air blast gin of the pneumatic moting type comprising a saw cylinder and cooperating ginning ribs, means forming a moting chamber confronting the saw cylinder in the region of centrifugal mote discharge adjacent said ribs, a mote discharge duct with which said moting chamber communicates, a lint discharge flue confronting said saw cylinder in a region remote from said ribs, and a pneumatic system for mote disposal and lint removal comprising a moting blast nozzle in said moting chamber and a lint removing blast nozzle in operative relation to said saw cylinder and lint flue, a compressed air reservoir, conduits from said reservoir to said nozzles, that conduit which serves the moting blast nozzle extending parallel to said nozzle and opening thereinto uniformly throughout the length of said nozzle, said conduit having an extension beyond one end of said nozzle, through which extension said reservoir communicates with said nozzle, and a valve in said extension controlling the communication of said reservoir with said conduit for varying the volume of air delivered to said conduit and an air volume regulating valve in the conduit to said moting blast nozzle.

2. Air blast gin of the pneumatic moting type comprising a saw cylinder and cooperating ginning ribs, means forming a moting chamber confronting the saw cylinder substantially throughout its length in the region of centrifugal mote discharge adjacent said ribs, a mote discharge duct with which said moting chamber communicates, a lint discharge flue confronting said saw cylinder in a region remote from said ribs, and a pneumatic system for mote disposal and lint removal comprising a moting blast nozzle in said moting chamber extending substantially throughout the length thereof and a lint blast nozzle directed tangentially of said saw cylinder toward said lint flue, a compressed air reservoir, a conduit from said reservoir to said lint blast nozzle, a conduit from said reservoir to said moting blast nozzle communicating therewith throughout the length of said nozzle and having an open ended extension to one side of said nozzle, said reservoir communicating with said last named conduit through said extension, and an air volume regulating valve in said extension formed as a removable closure for the

open end of said extension and controlling communication of said reservoir with said conduit.

3. Air blast gin of the pneumatic moting type comprising a saw cylinder and cooperating ginning ribs, means forming a moting chamber confronting the saw cylinder in the region of centrifugal mote discharge adjacent said ribs and extending substantially throughout the length of said saw cylinder, a mote discharge duct with which said moting chamber communicates, a lint discharge flue confronting said saw cylinder in a region remote from said ribs, and a pneumatic system for mote disposal and lint removal comprising a moting blast nozzle in said moting chamber having a linear orifice extending substantially throughout the length of said moting chamber, and a lint blast nozzle directed tangentially of said saw cylinder toward said lint flue, a compressed air reservoir, a conduit from said reservoir to said lint blast nozzle, a conduit communicating with said moting blast nozzle substantially throughout the length of said linear orifice, said conduit having a cylindrical extension at one end beyond said orifice, a conduit communicating between said reservoir and said extension and a rotatable valve comprising a cylindrical sleeve fitting said extension having its circumferential wall discontinuous in the zone of said communicating conduit whereby upon rotation of said valve the mouth of said communicating conduit may be more or less occluded.

4. Air blast gin as claimed in claim 3, said cylindrical valve being removably inserted in the open end of said extension and forming a closure therefor.

5. Air blast gin of the type having a saw cylinder operating in conjunction with ginning ribs, having a lint discharge flue with its mouth in proximity to the periphery of the saw cylinder at a point sufficiently distant from said ribs to provide an intervening space for the centrifugal discharge of the motes and trash carried on the lint mass adherent to the saw cylinder, and having a lint removing blast nozzle adjacent the mouth of the lint flue, in combination with a pneumatic moting system including a mote discharge duct having a relatively narrow portion debouching into a flared mouth defined between upper and lower walls, confronting said saw cylinder in the region of centrifugal mote discharge, a moting blast nozzle having a linear orifice along the lower edge of said lower wall directed away from said saw cylinder for blowing a sheet-like blast along said lower wall and into said mote duct, said lower wall and said sheet-like blast being in the path of direct impingement of the centrifugally discharged particles, said blast by venturi action creating suction in said flared mouth for evacuating the lighter suspended trash by way of said mote duct, and countering the down draft produced by rotation of the lint-laden saw cylinder, which would

otherwise draw said lighter trash into said lint flue, a compressed air reservoir, a conduit connecting said reservoir to said lint removing blast nozzle, a conduit communicating with the moting blast nozzle throughout the length of its orifice and having an end extension to one side of said moting blast nozzle, a conduit communicating between said reservoir and said extension and a valve in said extension for controlling the volume of air supplied by said reservoir to said moting blast nozzle, said extension of said moting blast nozzle conduit being cylindrical and said valve being a cylinder sleeve rotatably fitting within said extension, forming an end closure therefor and having its circumferential wall discontinuous in the zone of said communicating conduit whereby upon rotation of said valve the cross-sectional area of said communicating conduit may be varied.

6. Air blast gin of the type having a saw cylinder operating in conjunction with ginning ribs, having a lint discharge flue with its mouth in proximity to the periphery of the saw cylinder at a point sufficiently distant from said ribs to provide an intervening space for the centrifugal discharge of the motes and trash carried on the lint mass adherent to the saw cylinder, and having a lint removing blast nozzle adjacent the mouth of the lint flue, in combination with a pneumatic moting system including a mote discharge duct having a relatively narrow portion debouching into a flared mouth defined between upper and lower walls, confronting said saw cylinder in the region of centrifugal mote discharge, a moting blast nozzle having a linear orifice along the lower edge of said lower wall directed away from said saw cylinder for blowing a sheet-like blast along said lower wall and into said mote duct, said lower wall and said sheet-like blast being in the path of direct impingement of the centrifugally discharged particles, said blast by venturi action creating suction in said flared mouth for evacuating the lighter suspended trash by way of said mote duct, and countering the down draft produced by rotation of the lint-laden saw cylinder, which would otherwise draw said lighter trash into said line flue, a compressed air reservoir, a conduit connecting said reservoir to said lint removing blast nozzle, a conduit communicating with the moting blast nozzle throughout the length of its orifice and having a cylindrical end extension to one side of said moting blast nozzle, a conduit communicating between said reservoir and said extension, and a cylindrical sleeve rotatably fitting within said extension forming an end closure therefor and having its circumferential wall discontinuous in the zone of said communicating conduit whereby upon rotation of said valve the cross-sectional area of said communicating conduit may be varied.

JEFFREY J. WALLACE.
